DAVID ROBERT YARNALL AND JOSEPH KILDARE, OF PHILADELPHIA, PENNSYLVANIA,
ASSIGNORS TO YARNALL-WARING COMPANY, OF PHILADELPHIA, PENNSYLVANIA,
A CORPORATION OF PENNSYLVANIA

PACKING FOR PLUNGERS

Application filed January 4, 1927. Serial No. 159,006.

Our invention relates to packing for longitudinally movable shafts, rods and plungers.

The main purpose of our invention is to armor or protect the packing so as to retain it as a compact body against injury.

A further purpose is to use the compression of a molded ring to force out a protective shield against the plunger securing the benefit of metallic packing.

10 A further purpose is to combine edges of metallic packing at one end with non-metallic packing at the other, thus protecting against seepage past the metallic packing.

15 A further purpose in valve use is to protect from blow-off blast at a certain part of the travel of the plunger, relieving from the erosion which would otherwise take place in molded packing in some types of valve.

20 We have preferred to illustrate our invention in two applications only and in but two forms among the many applications and forms to which it may be suited, selecting constructions which are practical, efficient and inexpensive and which at the same time well illustrate the principles of the invention.

Figures 1 and 2 are fragmentary longitudinal sections of a valve to which our invention may be applied.

30 Figure 3 is a longitudinal section of a pump plunger gland packing further illustrating our invention.

Figures 4 and 5 are enlarged sections of slightly different forms of our packing.

35 In the drawings similar numerals indicate like parts.

We show in Figures 4 and 5 enlarged sections of packing adapted to any of many different uses. It comprises a non-metallic annular body 5 upon which is or are secured metallic facing 6 or metallic facings 6', 6'' covering a part of the interior by a shell or shield 7 and a part or all of a transverse face 8 or 8'. In Figure 5 two facings 6', 6'' are shown.

45 Either construction gives the benefit both of metallic packing in the inner metal shell or shield and non-metallic packing beneath the shell at 9. We do not, of course, limit ourselves to any particular material but for information in practicing our invention will

state that we have secured good results with a molded body composed largely of asbestos with small amounts of graphite and rubber and a Monel metal shield.

We show the packing as applied to two types of valve and to a pump plunger, selecting these illustrations as typical of varied packing needs.

55 In Figure 1 the body 10 is provided with upper packing 11 and lower packing 12 held in place by a shell ring 13 above the packing and a liner 14 below. The packing is compressed by any suitable means, here shown as the yoke 15 secured to the body as by bolts 16. Both packings may to advantage be of our novel form.

60 The body is supplied with inlet 17 and outlet 18 and the inlet 17 leads into a channel 19 about the lining so that a plurality of openings 20 permit passage of inlet fluid to the interior of the valve. The yoke mounts a threaded stem 21 held against longitudinal movement within the yoke and turned by wheel 22. The stem operates the plunger 23 comprising, effectively in the illustration a plug 24 and a sleeve 25. The sleeve 25 is apertured at 26 so as, in open position, to transmit water, steam and dirt from the inlet to the interior of the plunger, and hence to the outlet.

65 The upper packing is constantly engaging the uniform plunger surface and is subject to no special wear or injury. The lower packing is much more severely used.

70 As will be seen in the illustration, closing movement of the plunger will cause the lower portions of the openings 26 to expose the lower packing before the upper part of the openings ceases to register in part with the openings 20, as a result of which the lower packing will be exposed to a considerable blast of fluid from the time at which this exposure of the packing starts until the openings in the plunger cease to register at all with the effective openings in the valve body. This causes a very considerable erosion due to impact of water, steam and dirt against the lower packing.

75 80 85 90 95 100 In the form shown in Figure 2 the same

reference characters have been applied to parts corresponding to those in Figure 1 but using primes where the parts differ. Here the form of packing is that seen in Figure 5 and the special fluid-blast cause for erosion above has been avoided by increasing the distance parallel to the axis between the openings 15 and the packing so that inlet of fluid is shut off at all times when the packing 10 is exposed. However, passage of the openings in the plunger over the packing here as in Figure 1 results in excessive mechanical wear of the packing.

The two shells 6¹ and 6² are duplicates, 15 protecting opposite faces of the packing and comprising forms against which or by which the non-metallic material is compressed. These forms are effective even with different shape of the seats by which the packing ring 20 is engaged, but are intended to cooperate with seats of the same shape.

This construction not only permits the packing to be put in place with either face out but permits it to be used in one position 25 and then reversed in position if desired.

In Figure 3 the packing surrounds the plunger 27 of a pump. It rests in an annular recess 28 where it is compressed by gland 29 held by bolts 30.

30 In both forms of our invention the corners 31 of the packing are chamfered to fit a corresponding cross section of recess and the ring is correspondingly chamfered at 31'.

The tapered lip 32 of the lower end of 35 the shell 7 of the form in Figure 4 presses the shell inwardly with compression upon the combined packing in an axial direction. At the same time the compression of the body 5 of the packing tends to squeeze the packing 40 out into tighter contact with the plunger where the non-metallic packing is exposed so as to prevent seepage past the packing.

It will be obvious that the armor or protective shell is advantageous not only for 45 the actual physical protection against fluid or mechanical erosion but also because it secures the combined effects of metallic and non-metallic packing.

In view of our invention and disclosure 50 variations and modifications to meet individual whim or particular need will doubtless become evident to others skilled in the art, to obtain part or all of the benefits of our invention without copying the structures 55 shown, and we, therefore, claim all such in so far as they fall within the reasonable spirit and scope of our invention.

Having thus described our invention, what 60 we claim as new and desire to secure by Letters Patent is:—

1. A packing ring comprising a molded body of asbestos, graphite and rubber in combination with a nickel alloy protective casing therefor covering one inner edge of the pack- 65 ing.

2. An annular packing for packing a longitudinally movable shaft, comprising a molded ring of non-metallic material in combination with a shell of metal covering a part only of the inner cylindrical surface of the ring and extending over part of the flat annular surface of the ring, the inner cylindrical surface of the shell and the inner cylindrical surface of the packing not covered by the shell being flush one with the other, and the end of the inner cylindrical surface of the shell adjoining the extension over the flat annular surface of the molded ring being tapered outwardly and toward the extension to force the flat annular surface of the metallic ring inwardly when the packing is compressed.
